UNITED STATES PATENT OFFICE.

FRANK LAUHOFF, OF DETROIT, MICHIGAN, ASSIGNOR TO THE AMERICAN TOBACCO COMPANY, A CORPORATION OF NEW JERSEY.

MACHINE FOR TREATING TOBACCO-STEMS.

1,099,260.

Specification of Letters Patent.

Patented June 9, 1914.

Application filed March 27, 1897. Serial No. 629,481.

To all whom it may concern:

Be it known that I, FRANK LAUHOFF, citizen of the United States, residing at Detroit, county of Wayne, State of Michigan, have invented a certain new and useful Improvement in Machines for Treating Tobacco-Stems, and declare the following to be a full, clear, and exact description of the same, such as will enable others skilled in the art to which it appertains to make and use the same, reference being had to the accompanying drawings, which form a part of this specification.

My invention has for its object a machine for treating tobacco stems, so as to produce a material that may be readily granulated to a product similar to granulated leaf stems, and it consists of the construction, combination and arrangement of devices and appliances hereinafter described and claimed, and illustrated in the accompanying drawings, in which—

Figure 1 is a side elevation. Fig. 2 is a plan view. Fig. 3 is a vertical section on the line 3—3 of Fig. 2. Fig. 4 is a vertical section on the line 4—4 of Fig. 2. Fig. 5 is a vertical section on the line 5—5 of Fig. 2. Fig. 6 is a view partly in plan and partly in horizontal section showing portions of the device. Fig. 7 is an enlarged view in vertical cross section through one of the knives and related devices. Fig. 8 is a partial side elevation showing one of the brackets L engaged upon the support showing parts broken away. Fig. 9 is a detail view in side elevation of one of said brackets engaged upon the support.

It is well understood that in the manufacture of tobacco a great waste has heretofore occurred from inability to use the tobacco stems to any very considerable extent. Various efforts have been made to utilize them, but without satisfactory results hitherto, but my invention is designed and adapted to so flatten the stems as to enable the product to be used up in the manufacture of certain kinds of tobacco, as granulated smoking tobacco, for example, without injuring the quality of the tobacco, or cheapening its value, thereby effecting a very great saving to tobacco manufacturers, in enabling them to use up their stems which have commonly gone to waste. I accomplish my object by providing a machine which

will effectually flatten the stems into a thin film, the stems being reduced to a thin tissue, readily granulated and having the general consistency and resemblance when granulated, of the leaf portions stripped from the stems. To accomplish this result, I carry out my invention as follows:

In the drawings, A represents any suitable support, upon which are mounted two rotatable flattening rolls B and B¹, one of said rolls, as the roll B being rotatable at a higher rate of speed than the other, thereby giving to the two rolls a differential speed, causing considerable friction and consequent heating of the rolls. It is important to have the rolls heated to a proper temperature to secure satisfactory results in treating the stems, yet too great a temperature of the rolls will render the machine incapable of proper operation, and it is very essential therefore, that means be provided to govern the temperature of the rolls as desired. To this end my invention contemplates constructing the rolls B, B¹ hollow, as shown in Figs. 4 and 5 particularly, and also to construct the axles or shafts b and b¹ of said rolls, respectively, each with a water inlet channel b² communicating with the inner chamber B² of the roll, each axle being also constructed with an outlet channel b³ communicating with the chamber of the roll, thereby effectually providing for water circulation through the axles or shafts of the rolls to cool said shafts in their bearings, and also to cool the rolls to a proper temperature.

C denotes the boxes of the shafts or axles of the rolls. One feature of my invention aims to provide means for cooling said boxes also. To secure this result, each of said boxes is constructed with an inner chamber C¹, preferably formed in a hollow back portion C², through which water may circulate. Into each box is therefore led a water inlet pipe, and a water outlet pipe. It will be understood that the pressure upon the shafts, being chiefly toward the back, or away from the meeting edges of the rolls, the back of the boxes will be heated most, and I therefore prefer to construct the backs of the boxes hollow to receive the water circulation. I prefer to provide a main feed water pipe D, which may lead into one of said boxes C, as at the base thereof, an outlet pipe D¹

leading from the corresponding box. From the pipe D¹ may lead a pipe D² into the shaft of the adjacent roll. The pipe D¹ may also be connected with an additional pipe D³, as by a flexible or hose connection D⁴, the pipe D³ being led into the other box, at the same side of the machine. A pipe D⁵ may also be led from the pipe D³ into the shaft of the other roll. As already specified, 10 the water led into the shafts of the rolls is conducted into the interior chambers of the rolls and is discharged therefrom at the opposite side of the machine, as through pipes D⁶ and D⁷. The water fed into the adjacent 15 box by the pipe D³ may be discharged therefrom through a pipe D⁸. The boxes at the opposite side of the machine may be supplied with feed water and outlet pipes, also in any suitable manner. Thus, for example, 20 E may denote a feed inlet pipe leading into the adjacent box, while E' denotes an outlet pipe leading therefrom, and to the next box, an outlet pipe E² leading from the last named box. The rolls may be driven in any 25 desired manner, as by a driving pulley F upon one of the shafts of the rolls, the opposite ends of the shafts being geared together as by gears F¹ and F². It is found desirable that one of the rolls should have a yielding 30 engagement upon the support A and that it should be adjustable toward and from the opposite roll, so that it may be set as snugly against the other roll as may be desired to accomplish the desired results. One of the 35 rolls and its boxes may have a fixed engagement upon the support or frame work of the machine. I do not limit myself solely to any given construction, whereby one of the rolls may be adjusted, but as shown in the drawings, this may be accomplished by providing 40 the support or frame-work A with a guide or way G, at each side of the machine, the boxes of the adjustable roller having a movable engagement upon said guide or way. In addition, the machine is provided 45 with guides or ways G¹ at the upper ends or tops of the boxes upon which the boxes of the adjustable roller may also have a movable engagement. I prefer that the boxes, at 50 the bottom and top of each, should be provided with lateral flanges to project over and astride of the guides or ways G and G¹. The boxes of the adjacent roller may be adjusted by screws H suitably supported. To 55 provide for a yielding of the adjacent roller I interpose springs, indicated at H¹ bearing against the adjustable boxes located between said boxes and the adjacent extremities of the adjusting screws. It sometimes happens 60 that nails or other foreign matter will pass into the machine between the rolls, but by permitting one of the rolls to yield such foreign matter may pass between the rolls without serious injury to the machine.

65 The adjusting screws are shown having a

threaded engagement in uprights H² engaged with the adjacent extremities of the guides G and G¹. The opposite extremities of said guides may be bolted down to the frame-work of the machine as by bolts J, 70 thereby holding the boxes firmly in position.

The tobacco stems are fed to the rolls in any suitable manner, as upon a feeding chute, indicated at K. To flatten the stems to a tissue requires a very considerable pressure between the rolls, and the rolls being heated to a desired temperature the product will stick firmly to the rolls, chiefly to the roll rotating at the higher speed. To separate the product from the rolls, I provide 75 each of the rolls with mechanism to cut the product off from the rolls. As shown in the drawings, this cutting mechanism may consist of brackets L having an adjustable engagement upon the bed or frame A of the 80 machine, in any suitable manner. Thus the brackets may be formed with a laterally projecting flange L⁷ provided with elongated slots 7 through which bolts l' engage the brackets upon said bed, with an intervening 85 friction plate l⁶ between the head of the bolts and said flange, the bolts being of just sufficient length to engage the brackets upon the support without unduly binding the same thereupon, but permitting the adjustment of said brackets. The brackets L are 90 constructed with a base or bed L¹ upon which rests an adjustable plate or knife-holder L² made reciprocatory by means of 95 adjusting screws l² engaged with the base or bed L¹, and with said plate or knife-holder. The brackets L are grooved, as indicated at Fig. 9 at l⁷ to receive the extremities of the knife-holder L², while the bed L¹ is preferably formed with an upturned flange, as 100 shown, to receive the adjusting screws l².

L³ denotes a cap serving as a clamp also to hold a blade or knife L⁴ between said cap and the plate or holder L², said cap may be engaged upon said plate or knife holder by 110 means of screws l³. In this manner it will be evident, that the knife blade L⁴ may readily be adjusted toward and from the adjacent roll. The holder L² and cap are preferably constructed with curved bearings toward their lower edges on their adjacent faces, as indicated at l⁴ and l⁵, whereby the edge of the knife may be adjusted vertically as may be required, the knife being permitted a rocking movement upon said bearings l⁴ and l⁵, the edge of the knife being 115 adjusted vertically by means of screws L⁵ passing through the cap and bearing upon the knife-blade above the bearings l⁴ and l⁵. In this manner the knife blades may be set 120 snugly against the adjacent rolls. The brackets L are also preferably connected with the adjacent boxes in any suitable manner, so that the boxes and the corresponding 125 knife-blade or cutting mechanism may 130

be adjusted and yield simultaneously with the corresponding roll. Should a nail or some other hard foreign substance be carried through the rolls, it will be evident that 5 if the cutting mechanism was not arranged to yield with the roll and its boxes, the roll backing against the edge of the knife would take the cutting edge off the knife. This would obviously be the case if the cutting mechanism was rigid in its location. But 10 my invention contemplates the simultaneous yielding of the cutting mechanism and its adjustment with the yielding and adjustment of the roll and its boxes. As shown, 15 the brackets L are connected with the boxes by means of arms L^e.

M denotes bridges at the sides of the machine extending across from one box to the other at each side of the machine to hold 20 the boxes more snugly in position. These bridges may be fastened upon the support or frame of the machine in any suitable manner, as by bolts m.

It will be understood that the water pipes 25 may be provided with any suitable valves, indicated at c to control the circulation therethrough. I prefer that the outlet pipes D^e and D^f leading out of the shafts should discharge into a funnel d. This funnel may 30 be open so that the flow of the water can be watched.

N denotes the product being cut off from the rolls by the knife blades. It will be understood that the product may be carried 35 from the machine in any desired manner.

The operation of the machine will be understood, the rolls being heated to a proper temperature, the stems are fed thereto, the product sticking to the rolls and being cut off therefrom in a thin film by the knives. The water circulation prevents any overheating of the rolls and may be held to such a point of adjustment as to properly control the temperature of the rolls. When 45 the product is cut off from the rolls by the knife blades, the blades leave the roll perfectly clean to the rear of the knife edge so that as the rolls rotate they are in condition to receive succeeding stems fed thereto, 50 and accomplish efficient work in flattening the same. Should the knife blade become dull, the caps may be readily removed and sharpened blades be replaced in the cutting mechanism. The stems, it will be understood, are fed 55 to the machine in a properly moistened or pliable condition. The knife holder or plate L² is engaged at its extremities in corresponding recesses in the brackets L, as indicated in dotted lines in Fig. 6. The cells 60 of the tobacco stems are occupied with a gummy substance, which when the stem is moistened and heated and pressed to a tissue, will coat the product with a sort of film or glaze analogous to the appearance of 65 the natural leaf portion.

It is obviously, very important to have the adjustable roll and the knife to move simultaneously so as not to dull the knife, as when some hard foreign substance passes between the rolls and crowds the rolls 70 apart. By having the cutting device so connected with the adjustable boxes of the roller, the knife will give or recede with every receding movement or jar upon the roll, the knife not only being prevented from 75 being dulled, but is also held up and maintained in a uniform position relative to the roll all the time. By constructing the knife holder L² with the curved bearing L⁴ and the cap L³ with the curved bearing L⁵, 80 it is evident that if the knife does not set uniformly with its edge across its entire length snugly against the roll, the knife can readily be adjusted at any desired point by means of the set screws L⁶, which, as shown 85 in Fig. 6 are located in different positions along the length of the knife, whereby the knife may be evenly and uniformly set throughout in proper contact with the surface of the roll to secure the desired result 90 and an even cutting off of the stock adhering to the roll. It is important therefore to have various set screws bearing upon the knife along its length, whereby the operator may thus set and keep the knife in an even 95 contact all along its edge with the roll.

In the operation of the machine, as hereinbefore described, the rolls, together with the stock operated upon are heated, softening the contents of the cells in the tobacco 100 stems, enabling the contents of the cells when thus softened and subjected to the pressure of the rolls to be more effectually spread over the surface of the flattened product to glaze the surfaces of the product 105 over as the contents of the cells are thus spread in a softened condition over said surfaces, while, as already observed, at the same time the heating of the rolls and stock causes the flattened product to stick to the 110 roll necessitating its being cut off with a sharp knife. When so cut off, the contents of the cells of the stem coating the surfaces of the product gives to the product much the same form and appearance as that of the 115 natural leaf. It will be observed that the water pipes are arranged so as to feed a fresh supply of water continually through the rolls, the rolls being fed by the two pipes D² and D⁵; the water after passing through 120 the corresponding roll not returning through the other roll, but the two rolls being provided with independent discharges of the water therefrom, so that each roll is thus provided with its own independent 125 water circulation. By this means each roll may be kept of desired temperature in a ready and convenient manner. The inlet pipes connected into the corresponding rolls, are preferably connected thereinto by means 130

of an intervening stuffing box, indicated at Q in Fig. 5 of any suitable construction, a pipe Q¹ rotating with the roll having a rotatable connection in the stuffing box. So 5 also the outlet channels of the axles of the rolls at the opposite ends thereof, as above described, preferably discharge into the funnels d through intervening pipes D⁶, D⁷, said pipes D⁶ and D⁷ rotatable with the corresponding 10 rolls and revolvably connected in the corresponding funnels, as shown. It will be understood, however, that, while this arrangement of the water circulating pipes is preferred, any other suitable arrangement 15 for circulating the liquid through the rolls to secure the desired control of the temperature of the rolls may be used.

The process and product described herein are covered by my Patent No. 772,892, dated 20 October 18th, 1904.

What I claim as my invention is:

1. In a machine for the purpose described, the combination of a support, the rolls, transverse lower and upper guides at each 25 side of the machine upon said support, boxes for the shafts of said rolls between said lower and said upper guides, the boxes of the shaft for one of said rolls being adjustable upon said support between said guides, 30 means to adjust the position of the movable boxes to adjust the corresponding roll toward and from the other roll, and transverse bridges at the sides of the machine located above the upper guides and bearing 35 at their extremities upon the upper guides, said bridges extending, respectively, across each end of the machine from one of said boxes to the box of the corresponding roll to hold said boxes more snugly in position, 40 and means to secure said bridges upon the support of the machine, substantially as set forth.

2. The combination of horizontal rolls and their shafts constructed to provide 45 water circulation therethrough, boxes for said shafts, and means to feed water through each of said rolls, the water circulation through the rolls being independent the one of the other, the boxes of one of said shafts 50 made adjustable to adjust one of said rolls horizontally throughout its entire length toward and from the other roll, substantially as described.

3. The combination of a support, the rolls, 55 and cutting mechanism arranged to cut the stock off from the rolls, said cutting mechanism having an adjustable engagement on said support adjacent to said rolls, one of said rolls and the adjacent cutting mechanism 60 having a simultaneously yielding movement toward and from the other roll, substantially as described.

4. The combination of the rotatable rolls, 65 the support, the knives arranged upon said support adjacent to said rolls, said knives be-

ing adjustable laterally in a direction toward and from the adjacent roll and having a rocking movement inside of the support and relatively to the support, and essentially at right angles to the endwise movement of said 70 knives, whereby the knives may be brought closely into contact with the corresponding rolls, substantially as described.

5. The combination with the rotatable rolls, the support, an adjustable knife holder, 75 including a cap, a knife held in place between edges on the holder and the cap and arranged to cut the stock off from the rolls, the brackets, the base engaged with said brackets to support said knife holder, and 80 knife, means to adjust the holder toward and from the roll, and means to vertically tilt the knife, whereby the edge of the knife may be brought closely into contact with the corresponding roll, for the purpose set forth. 85

6. The combination of the support, the rotatable rolls, adjustable boxes carrying one of said rolls, a knife holder adjustable toward and from the adjacent roll, adjustable brackets to support the knife holder, a 90 knife in engagement with said holder, and means to vertically tilt the edge of the knife to bring said edge into close contact with the corresponding roll, said brackets connected with the boxes of one of said rolls, 95 whereby said brackets and corresponding boxes may yield simultaneously, substantially as described.

7. The combination of the support, the rotatable rolls, the brackets engaged upon said 100 support, a knife holder, a base connected with said brackets to support said knife holder, an adjusting screw to adjust the knife holder upon the base toward and from the adjacent roll, a cap, an intervening knife 105 located between the knife holder and the cap, said knife holder and cap provided with adjacent edges bearing upon the knife and forming a fulcrum for the knife, and set screws at intervals lengthwise of the knife 110 to vertically adjust the knife to tilt the knife upon said fulcrum, whereby the knife may be brought closely into contact with the corresponding roll, substantially as described.

8. The combination of the support, the rotatable rolls, brackets engaged upon said support, a connecting base uniting said brackets, a knife holder upon said base, a knife upon 115 said knife holder, a cap forming a part of the knife holder to clamp said knife in place, means connected with said base to adjust the knife holder, and means engaged with said cap to adjust the knife, substantially as described.

9. The combination of a yieldingly mounted roll, a knife acting upon said roll and mounted to tilt toward and from the surface of the roll, means for tilting said knife to adjust it relatively to the roll and holding it rigidly in adjusted position, and a sup- 125 130

port on which the knife is mounted having a simultaneous yielding movement with the roll, substantially as described.

10. The combination of a roll, a knife acting upon said roll, a rigid fulcrum on which the knife is mounted to move edgewise and tilt toward and from the surface of the roll, and set screws at intervals lengthwise of the knife arranged to tilt the knife upon said 5 fulcrum to adjust the knife relatively to the roll and hold it rigidly in adjusted position, substantially as described.

11. In a machine for treating tobacco stems, the combination of stem flattening 15 rolls rotating at different surface speeds and set close together under such pressure as to compress the stems into a thin film on said rolls, means for circulating liquid through said rolls to secure the desired temperature 20 of the rolls, knives mounted on rigid fulcrums to tilt toward and from the surface of said rolls and arranged to cut the product off said rolls in a thin film, and means for tilting said knives to adjust them relatively 25 to the rolls and hold them rigidly in adjusted position, substantially as described.

12. In a machine for treating tobacco stems, the combination of stem flattening rolls rotating at different surface speeds and 30 set close together under such pressure as to compress the stems into a thin film on said rolls, means for circulating liquid through said rolls to secure the desired temperature of the rolls, knives mounted on rigid fulcrums to tilt toward and from the surface of 35 said rolls and arranged to cut the product off said rolls in a thin film, and set screws set at intervals longitudinally of the knives for tilting said knives to adjust them 40 relatively to the rolls and hold them in adjusted position, substantially as described.

13. In a machine for treating tobacco stems, the combination of stem flattening rolls rotating at different surface speeds and 45 set close together under such pressure as to compress the stems into a thin film upon said rolls, means for circulating liquid through said rolls to control the temperature of said 50 rolls, one of said rolls being yieldingly mounted to move toward and from the other, knives mounted upon fulcrums to tilt toward and from the surface of said rolls and arranged to cut the product off said rolls in a thin film, set screws 55 at intervals longitudinally of said knives for tilting said knives to adjust them toward and from the rolls and hold them rigidly in adjusted position, and supports for said

knives, the support for the knife co-acting with the yieldingly mounted roll having a 60 simultaneous yielding movement with said roll, substantially as described.

14. The combination of a yielding roll, a knife acting upon said roll, a rigid fulcrum on which the knife is mounted to move edgewise and tilt toward and from the surface of the roll, and set screws at intervals lengthwise of the knife arranged to tilt the knife upon 65 said fulcrum to adjust the knife relatively to the roll and hold it rigidly in adjusted 70 position, and a support for the knife fulcrum having a simultaneous yielding movement with the roll, substantially as described.

15. In a machine for treating tobacco stems, the combination of stem flattening 75 rolls rotating at different surface speeds and set close together under such pressure as to compress the stems into a thin film upon said rolls, one of said rolls being yieldingly mounted to move toward and from the other 80 roll, and cutters rigidly mounted relatively to the rolls and arranged to cut the product off said rolls in a thin film, the cutter for the yieldingly mounted roll being mounted to move with said roll in its movement 85 toward and from the other roll, substantially as described.

16. In a machine for treating tobacco stems, the combination of stem flattening 90 rolls rotating at different surface speeds and set close together under such pressure as to compress the stems into a thin film on said rolls, means for circulating liquid through said rolls to control the temperature of said 95 rolls, and cutting devices arranged to cut the product off said rolls in a thin film, substantially as described.

17. In a machine for treating tobacco stems, the combination of stem flattening 100 rolls rotating at different surface speeds and set close together under such pressure as to compress the stems into a thin film on said rolls, means for circulating liquid through said rolls to secure the desired temperature 105 of the rolls, knives mounted to tilt toward and from the surface of said rolls and arranged to cut the product off said rolls in a thin film, and set screws at intervals lengthwise of the knives to adjust them relatively 110 to the rolls, substantially as described.

In testimony whereof, I sign this specification in the presence of two witnesses.

FRANK LAUHOFF.
